UNITED STATES PATENT OFFICE.

ROBERT B. CLAGGETT, OF LOUISVILLE, KENTUCKY.

BUCKLE.

1,364,544.

Specification of Letters Patent.

Patented Jan. 4, 1921.

Application filed May 16, 1919. Serial No. 297,596.

To all whom it may concern:

Be it known that I, ROBERT B. CLAGGETT, a citizen of the United States, residing in the city of Louisville, county of Jefferson, 5 and State of Kentucky, have invented a new and useful Buckle, of which the following is a specification.

This invention relates to buckles.

Buckles are devices widely known, and 10 extensively used for fastening, they usually consist of a metal frame having a central cross bar to which a tongue is pivotally attached, it being of such length that the point thereof rests upon the forward bar of 15 the frame. In service the end of a strap is secured to the cross bar, and the end of another strap, or other end of the same strap, is passed under the front bar and the tongue engaged in a hole provided therein 20 for the purpose, the end is then tucked under the rear bar, between it and the strap. To release the strap, the loose end thereof is drawn back over the front bar, or toe, of the buckle and tension exerted on it to draw 25 the hole off the tongue, the tongue raised with the fingers, and the strap released. The tension on the strap tends to hold the tongue down rendering it very difficult to raise, especially if the strap is stiff, or the 30 fingers chilled.

An object of this invention is to provide a buckle so constructed that the tongue may be released without the use of the fingers.

With the foregoing and other objects in 35 view, the invention consists of the novel construction and arrangement of parts illustrated in the accompanying drawing, which forms a part of this specification, wherein is set forth an embodiment of the invention, 40 but it is to be understood that such changes and modifications may be resorted to as come within the scope of the claim appended hereunto.

In the drawings wherein similar reference characters designate like parts in the several views: Figure 1, is a side elevation of an embodiment of the invention shown as joining two straps: Fig. 2, a similar view showing the manner in which the tongue is 45 freed: Fig. 3, a detached perspective view of the front portion of the buckle: Fig. 4, a similar view of the rear portion of the buckle and Fig. 5 a perspective view of the buckle assembled.

50 The improved buckle comprises two parts, a rear, or heel, portion —10— and a front, or toe, portion —11— the two being pivot-

ally connected. The heel portion is preferably a rectangular frame, comprising side members —12— which are connected by 60 transverse bars —13 and 14—. A tongue —15— projects from the outer edge of one of the transverse bars as 13, being integral therewith, and extends upward at an angle to the plane of the frame. It is obvious 65 that a plurality of tongues may be employed if desired. The toe portion comprises a substantially U shaped part, comprising a cross bar —16— and connected parallel side members —17— extended substantially at right 70 angles therefrom. The side members terminating in eyes, or loops, —18— which are engaged around the front bar, 13, of the heel member, from which the tongue extends, the arrangement being such that the 75 point of the tongue rests upon the cross bar 16. In service, a strap —19— is connected with the center 13, in any usual, or suitable manner, and an end of a strap —20— is passed under the bar 16, up through the toe 80 of the buckle, and the tongue engaged therewith, as in the conventional form. To disengage the strap, tension is exerted on the loose end —21— as usual, then it is only necessary to exert pressure on the bar 14, of 85 the heel of the buckle, the depression whereof will raise the tongue, as it is integral therewith, clear of the strap, as shown in Fig. 2. As soon as the tension on the strap is released, the toe can be swung away from 90 the tongue so that it will offer no obstacle to the withdrawal of the strap, or accidentally catching in a hole.

Having thus described my invention so that any one can make and use the same, I 95 claim:

In a buckle, a heel portion comprising a rectangular frame consisting of front and rear bars joined by side members and having a rigid tongue extended from the front 100 bar at an angle to the plane of the frame, a strap affixed by one end to the said front bar and underlying the rear bar, a toe portion comprising a substantially U shaped member pivotally connected to the front bar 105 of the heel portion and adapted to receive the free end of the strap to be engaged with the tongue, the engagement being such that the front bar of the heel portion is freely rotatable by operation of the exposed rear bar to release the tongue regardless of tension on the strap. 110

ROBERT B. CLAGGETT.
